INVENTOR
RICHARD J. ROBERTS.

BY *Arthur L. Lee*
ATTY.

UNITED STATES PATENT OFFICE.

RICHARD J. ROBERTS, OF SAN FRANCISCO, CALIFORNIA.

PREHEATER FOR TYPE AND LEAD CASTING MACHINES.

Application filed September 24, 1927. Serial No. 221,745.

My invention relates to preheaters for melting metal preparatory for introduction into lead and slug casting machines and the like.

5 In the operation of lead and slug casting machines, and the like, pigs of casting metal are inserted in a melting pot forming a part of the casting machine. Said melting pots are heated in various ways, but as 10 the consumption of melted metal is very rapid when the machine is in operation, the very frequent introduction of cold pigs of metal into the pot cools the metal and retards the efficient operation of the machine, it being frequently necessary to slow down 15 the machine or stop operation entirely until the supply of melted metal can be built up to meet normal requirements. The primary object of my present invention is 20 therefore to provide an improved device for preheating the casting metal whereby the metal may be delivered to the melting pot of the machine preheated to a molten condition whereby the requisite supply of 25 metal for efficient operation of the machine may be maintained at all times.

A further object is to provide an improved device of the character described whereby metal to be supplied to a casting 30 machine is melted by electrical means before being introduced into the machine.

Another object is to provide an improved 35 electrically heated device wherein the electrical heating units are automatically cut out of the energizing circuit when the supply of metal is cut off.

A further object is to provide an improved device relatively light and compact and which may be easily placed in service 40 without altering the machines and equipment to which it is applied.

A still further object is to provide an improved device of the character described which is simple in construction and highly 45 efficient in operation.

I accomplish these and other objects by means of the improved device disclosed in the drawings forming a part of the present application wherein like characters of reference are used to designate similar parts throughout the specification and drawings, and in which,

Fig. 1 is a broken front elevation of my improved preheater, the casing being shown 55 in section, and parts being broken away;

Fig. 2 is a vertical mid-section of the preheater;

Fig. 3 is a plan view of the preheater; and

Fig. 4 is a broken side elevation including 60 a wiring diagram illustrating the automatic circuit breaking means.

Referring to the drawings, my improved preheater consists of a pair of chamber blocks 1 bolted or otherwise secured together, said blocks having matching recesses forming a chamber 2 arranged to receive pigs of casting metal to be supplied to a lead and slug casting machine, or the like, not shown. An outlet 3, preferably of 65 tubular metal of high heating conductivity, is connected into the bottom of the chamber 2.

Electrical resistance heating units 4 are mounted in proximate relation to the outer 70 faces of the blocks 1, said units being secured and held in place by plate 6 secured by screws or other suitable securing elements 7 to hold the heating elements closely against the outer sides of the chamber 80 blocks 1. Thin sheets 8 of mica or other suitable electrical insulating material are inserted between the heating unit and the blocks 1 and plates 6.

The heating units are connected, in any 85 suitable manner, preferably in series, by suitable electrical connections 9 and 11 secured by binding posts 12 secured upon the base of the blocks 1, said binding posts being connected to the units through conductors 90 13 preferably connected onto the ends of the posts 12 to permit the replacement of heating elements without disturbing the wiring connections. The units 4 are connected to a suitable source of electrical 95 energy, not shown, in any convenient manner.

An automatic cut out switch designated in general by the numeral 16 is connected into the circuit to the heating units 4. The cut 100 out switch may be of any available construction; a form being conventionally illustrated wherein a movable contact arm 17 is arranged to be actuated by a relay 18 energized from the feed connections 19 to break connection between feed contacts 21 and 22 when a cut out contact 23 is moved to bridge cut out contacts 24 normally breaking the circuit to the relay 17. The contact 23 is carried upon an arm 26 secured upon the outer end 105

of a shaft 27 mounted within the upper edge of one of the chamber blocks 1. A lever 28 is mounted upon the shaft 27 within the chamber 2, said lever being arranged to be received within a recess 29 formed within the chamber and engaging the shaft 27 within an enlarged portion of said recess at the top of the block 1. A counter-weight 31 is secured upon the outer end of the shaft 27 to normally move the lever 28 outwardly from the recess 29 and across the chamber 2 as indicated in dotted lines in Fig. 2 of the drawings, and at the same time to move the arm 26 to carry the contact 23 into bridging relation to the contacts 24 as indicated in dotted lines in Fig. 4. A control switch 25 is mounted at any convenient place to break the feed connections when desired.

A casing 32 formed of asbestos or other suitable heat insulating material is mounted to substantially enclose the sides and bottom of the preheater and thereby reduce loss in heating efficiency. A suitable bail 33 is secured upon the top of the preheater whereby the same may be suspended in any convenient manner over the melting pot of a lead and slug casting machine.

In operation, my preheater is mounted or suspended by the bail 33 over the melting pot of the casting machine, and connected to a source of electrical energy. When the casting machine is to be placed in operation, the control switch 25 is closed and a pig of metal to be melted and delivered to the machine is inserted in the chamber 2, said metal serving to force the lever 28 into the recess 29 and thereby move the shaft to raise the counter-weight 31 and at the same time move the arm 26 and contact 23 out of engagement with the contacts 24. The heating units are thus energized and operate to rapidly heat the chamber and melt the metal therein, said metal draining off through the outlet 3 into the melting pot of the machine. After the initial heating of the chamber and when the first metal pig has been melted fresh pigs of the casting metal are inserted into the chamber at frequent intervals whereby a constant supply of melted metal may be delivered into the melting pot of the casting machine whereby said machine may be operated at full efficiency without cooling the metal in the melting pot by the introduction of metal pigs therein. So long as a supply of metal is maintained in the chamber 2, the lever 28 will remain in circuit closing position, and the heating elements will remain operative to maintain the temperature of the preheater. Should the metal become exhausted, or should the main control switch be inadvertently left closed when the machine is not in operation, the counterweight 29 operates by gravity to swing the arm 26 and contact 23 into engagement with the contacts 24, thereby closing a circuit through the relay 18

whereby the circuit is broken between the contacts 21 and 22, thereby cutting the heating units out of the circuit and thus preventing overheating of the units and the chamber, and preventing the waste of electrical energy. The outlet 3 is of greater heat conductivity than the chamber block 1 to insure that said outlet will prevent the freezing of metal within the outlet.

It will be noted that the electrical heating elements are arranged entirely outside of the chamber so that there can be no danger of injury to the elements should metal be permitted to harden within the chamber. At the same time, the elements are rendered readily removable so that new elements can be quickly installed when necessary.

While I have illustrated and described only the preferred embodiment of my invention, the device is of course subject to modification in numerous ways without departing from the spirit of my invention. I therefore do not wish to restrict myself to the specific form and construction illustrated, and described, but desire to avail myself of all modifications which may fall within the scope of the appended claims.

Having thus described my invention what I claim as new and desire to secure by Letters Patent is:

1. A preheater for lead and slug casting machines comprising a melting chamber arranged to receive pigs of casting metal; and electrical heating units arranged outside of the chamber and connected to a source of electrical energy to heat said chamber whereby the metal may be melted for delivery to the casting machine; and means for automatically disconnecting the heating units from the source of energy when a supply of metal is not maintained within the chamber.

2. A preheater for lead and slug casting machines comprising a melting chamber arranged to receive pigs of casting metal; plates secured upon the outer surfaces of the chamber; and electrical heating units secured between the plates and the outer surfaces of the chamber, said units being connected to a source of electrical energy for heating the chamber; current breaking means connected between the heating units and the source of electrical energy; and means controlled by the supply of metal within the chamber for actuating the circuit breaking means to break the circuit through the heating units when the supply of metal in the chamber is not maintained.

3. A preheater for lead and slug casting machines comprising a melting chamber formed from a pair of blocks having matching recesses forming a chamber to receive pigs of casting metal; a pair of electrical heating units arranged to be connected to a source of electrical energy; and plates se-

- cured upon the outer surfaces of the blocks and arranged to hold the units in proximate relation to said outer surfaces for heating the chamber.
5. 4. A preheater for lead and slug casting machine comprising a melting chamber formed from a pair of blocks having matching recesses forming a chamber to receive pigs of casting metal; a pair of electrical heating units arranged to be connected to a source of electrical energy; and plates secured upon the outer surfaces of the blocks and arranged to hold the units in proximate relation to said outer surfaces for heating the chamber; and an outlet connected into the bottom of the chamber, said outlet being formed of metal having higher heat conductivity than the blocks to insure the draining of melted metal from the chamber.
10. 5. A preheater for lead and slug casting machines comprising a pair of cast iron blocks secured together and having matching recesses formed in their adjacent faces to form a chamber arranged to receive pigs of casting metal; a pair of metal plates secured upon opposite outer faces of the blocks; electrical heating units mounted between the plates and the blocks, said units being arranged to be connected to a source of electrical energy for heating the chamber; a cut out switch connected between the units and the source of energy; an automatic control lever mounted within the chamber and arranged to be held in cut out circuit breaking position by metal within the chamber; and means actuated by the lever and the cut out switch for automatically breaking the circuit when the supply of metal to the chamber is not maintained.
15. 6. A preheater for lead and slug casting machines comprising a pair of cast iron blocks secured together and having matching recesses formed in their adjacent faces to form a chamber arranged to receive pigs of casting metal; a pair of metal plates secured upon opposite outer faces of the blocks; electrical heating units mounted between the plates and the blocks, said units being arranged to be connected to a source of electrical energy for heating the chamber; a cut out switch connected between the units and the source of energy; an automatic control lever mounted within the chamber and arranged to be held in cut out circuit breaking position by metal within the chamber; and means actuated by the lever and the cut out switch for automatically breaking the circuit when the supply of metal to the chamber is not maintained; and a heat insulating casing substantially enclosing the chamber and heating elements.
20. 5. A preheater for lead and slug casting machines comprising a pair of cast iron blocks secured together and having matching recesses formed in their adjacent faces to form a chamber arranged to receive pigs of casting metal; a pair of metal plates secured upon opposite outer faces of the blocks; electrical heating units mounted between the plates and the blocks, said units being arranged to be connected to a source of electrical energy for heating the chamber; a cut out switch connected between the units and the source of energy; an automatic control lever mounted within the chamber and arranged to be held in cut out circuit breaking position by metal within the chamber; and means actuated by the lever and the cut out switch for automatically breaking the circuit when the supply of metal to the chamber is not maintained; and a heat insulating casing substantially enclosing the chamber and heating elements.
25. 5. A preheater for lead and slug casting machines comprising a pair of cast iron blocks secured together and having matching recesses formed in their adjacent faces to form a chamber arranged to receive pigs of casting metal; a pair of metal plates secured upon opposite outer faces of the blocks; electrical heating units mounted between the plates and the blocks, said units being arranged to be connected to a source of electrical energy for heating the chamber; a cut out switch connected between the units and the source of energy; an automatic control lever mounted within the chamber and arranged to be held in cut out circuit breaking position by metal within the chamber; and means actuated by the lever and the cut out switch for automatically breaking the circuit when the supply of metal to the chamber is not maintained; and a heat insulating casing substantially enclosing the chamber and heating elements.
30. 5. A preheater for lead and slug casting machines comprising a pair of cast iron blocks secured together and having matching recesses formed in their adjacent faces to form a chamber arranged to receive pigs of casting metal; a pair of metal plates secured upon opposite outer faces of the blocks; electrical heating units mounted between the plates and the blocks, said units being arranged to be connected to a source of electrical energy for heating the chamber; a cut out switch connected between the units and the source of energy; an automatic control lever mounted within the chamber and arranged to be held in cut out circuit breaking position by metal within the chamber; and means actuated by the lever and the cut out switch for automatically breaking the circuit when the supply of metal to the chamber is not maintained; and a heat insulating casing substantially enclosing the chamber and heating elements.

In witness whereof, I hereunto set my signature.

RICHARD J. ROBERTS.
